UNITED STATES PATENT OFFICE.

EARLE RAWLINGS KNIGHT, OF NORWOOD, OHIO, ASSIGNOR TO THE BULLOCK ELECTRIC MANUFACTURING COMPANY, A CORPORATION OF OHIO.

BRUSH FOR DYNAMO-ELECTRIC MACHINES.

932,616.

Specification of Letters Patent. Patented Aug. 31, 1909.

Application filed February 7, 1906. Serial No. 299,871.

To all whom it may concern:

Be it known that I, EARLE R. KNIGHT, citizen of the United States, residing at Norwood, in the county of Hamilton and State 5 of Ohio, have invented certain new and useful Improvements in Brushes for Dynamo-Electric Machines, of which the following is a full, clear, and exact specification.

My invention relates to brushes for dynamo-electric machines.

Heretofore, the flexible conductors or "pig tails" have been connected to the carbon blocks in a variety of ways, none of which have proved entirely satisfactory.

15 The main object of my invention is to provide a connecting means for the flexible conductors and the carbon blocks which will be good both mechanically and electrically and which will permit the parts to be quickly 20 and inexpensively assembled.

A further object is to provide on the brush an improved form of brush holder guide plate.

In carrying out the first part of my invention, I provide a brush with a channel or opening extending through the body portion and connect the flexible conductor to the brush by means of a hollow rivet located in the channel. The end of the brush, provided with the channel is preferably copper plated so that there will be good electric contact between the rivet and the wall of the channel and between the conductor, which in the preferred construction is provided with a connection clip, and the body 35 of the brush.

In carrying out the second part of my invention I provide on one side of the brush a brush holder guide plate which extends over 40 the top of the brush. The plate and flexible conductor are preferably arranged on opposite sides of the brush and are held thereto by the hollow rivet.

45 My invention further consists in certain novel details of construction and combinations of elements described in the specification and set forth in the appended claims.

For a better understanding of my invention, reference is had to the accompanying 50 drawing, in which—

Figure 1 is a vertical section through the carbon brush showing the form of connection between the carbon block and the flexible conductor; Fig. 2 is a view in elevation

of one side of the brush; and Fig. 3 is a view 55 in elevation of the opposite side of the brush.

Referring now to the figures of the drawing, I have shown at 10 a brush for dynamo-electric machines, which brush is preferably 60 of carbon. The lower end of this brush is beveled so that a larger bearing surface between the brush and the commutator of the dynamo-electric machine can be obtained. The upper end of the brush is also beveled 65 for a purpose to be explained later. The brush is provided near its upper end with a transverse opening or channel 11 extending through the body of the brush from side to side. In order that there may be a good 70 electrical contact between the brush and the conductor connected thereto, the upper part of the brush is preferably copper plated as indicated at 12. The plating is done after the channel is provided so that the walls of 75 the latter as well as the outer parts of the brush are well coated.

The flexible conductor or "pig tail" is shown at 13. This flexible conductor has at 80 its outer end a clip 14, by means of which connection can be made between the brush and the brush holder or brush stud, and at its opposite end with a clip 15 by means of which the conductor can be securely held to the carbon block. The clip 15 is connected 85 to the carbon block by means of a hollow rivet 16 located within the channel 11. As is shown the clip surrounds the end of the rivet and is held between the body of the brush and the beaded or upset end 17 of the 90 rivet. The rivet 16 serves not only to hold the "pig tail" to the brush but also to hold the guide plate 18 thereto. This guide plate is on the opposite side of the brush from the pigtail and is held in place by the beaded 95 or upset end 19 of the opposite end of the rivet. This guide plate has two parallel sides 20 and 21 which are adapted to fit into a groove in the brush holder so as to guide the brush in its movement toward and away 100 from the commutator. In order that there may be no relative rotative movement between the carbon brush and the guide plate I extend the plate up over the end of the brush and for a short distance down the beveled 105 portion as shown at 22. It is seen that all rotative movement between the guide plate and the brush is prevented by this extension

at the end of the brush. The washer 23 in this case is between the guide plate and the end 19 of the rivet.

As is clearly shown in Fig. 1, the clip of 5 the conductor 13 bears against the copper plated portion of the brush. This will insure good electrical contact between the clip and the brush. As also appears from the drawing, the body of the rivet bears against 10 the copper plated wall of the channel. This also enhances the electric contact and reduces the resistance of the connection. When the ends of the rivet are upset or beaded, the body of the rivet is forced against the wall 15 of the channel and both the clip 15 and plate 18 are tightly held between the ends of the rivet and body of the carbon. Furthermore, when the connection is made a tool is preferably inserted within the rivet so as to expand 20 the ends of the latter and spread the material outward against the brush and the metal parts held thereto, so as to provide a more perfect connection than could be obtained were a solid rivet employed. I have 25 in this case shown the conductor connected to the brush by means of the rivet and clip. It may be desired to dispense with the clip, in which case the end of the flexible conductor will be held directly between the 30 brush and the end of the rivet.

I aim in my claims to cover all modifications which do not involve a departure from the spirit and scope of my invention.

What I claim as new and desire to secure 35 by Letters Patent is:—

1. A brush for dynamo-electric machines, comprising a carbon block having a channel

extending therethrough, a brush holder guide comprising a plate having parallel sides and having a portion extending up 40 over the end of said brush, a flexible conductor having a clip on the opposite side of said brush, and means for attaching said guide plate and said clip to the brush, said means comprising a rivet in said channel. 45

2. A brush for dynamo-electric machines, comprising a carbon block having a channel extending therethrough, a guide plate for a brush holder on one side of the brush, a conductor clip on the opposite side of said brush, and a hollow rivet in said channel 50 for connecting the plate and the clip to said brush.

3. A brush for dynamo-electric machines, comprising a carbon block having a channel 55 near its upper end, a portion of said brush including the walls of the channel being electroplated, a guide plate on one side of the brush, a conductor clip on the opposite side of said brush, and means for securing 60 both plates to the brush comprising a hollow rivet having its body portion located in said channel and its ends beaded over the plate and the clip.

4. In combination, a brush, and a brush 65 holder guide plate riveted only to one side thereof, said plate being bent over the end of the brush.

In testimony whereof I affix my signature, in the presence of two witnesses.

EARLE RAWLINGS KNIGHT.
